REARVIEW MIRROR

Joseph Fischer, Pelham Manor, N. Y.

Application April 3, 1953, Serial No. 24,348

Term of patent 14 years

(Cl. D14—6)

To all whom it may concern:

Be it known that I, Joseph Fischer, a citizen of the United States of America and a resident of Pelham Manor, county of Westchester, and State of New York, have invented a new, original, and ornamental Design for a Rearview Mirror, of which the following is a specification, reference being had to the accompanying drawings, forming a part thereof.

Fig. 1 is a back-side elevational view of a rearview mirror showing my new design;

Fig. 2 is a side-edge elevational view thereof; and

Fig. 3 is a top-edge elevational view.

The front surface not shown is a conventional flat mirror surface.

The dominant features of my design reside in the portion shown in full lines.

What is claimed is:

The ornamental design for a rearview mirror, substantially as shown and described.

JOSEPH FISCHER.
